UNITED STATES PATENT OFFICE.

GEORGE H. GILMAN, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

STONE-DRILLING ENGINE.

1,382,775.

Specification of Letters Patent. Patented June 28, 1921.

Application filed March 20, 1912. Serial No. 684,970.

To all whom it may concern:

Be it known that I, GEORGE H. GILMAN, a citizen of the United States, residing at Claremont, in the county of Sullivan and State of New Hampshire, have invented an Improvement in Stone-Drilling Engines, of which the following description, in connection with the accompanying drawings, is a specification, like characters on the drawings representing like parts.

This invention relates to stone working machines, and more particularly, though not exclusively, to stone or rock drilling engines, the object of the invention being to provide such an engine with improved means for removing or assisting in the removal of the cuttings from the drilled hole.

The invention will be best understood by reference to the following description, when taken in connection with the accompanying illustration of one specific embodiment thereof, while its scope will be more particularly pointed out in the appended claims.

In the drawings,—

Figure 1 is a central longitudinal section of a hammer drill embodying the invention.

Fig. 2 is a broken transverse section on an enlarged scale taken through the regulating valve shown in Fig. 1.

Referring to the drawings and to the illustrative embodiment of the invention therein shown, I have illustrated a hammer drill of a common type having a cylinder 1 and a hammer piston 2, the latter reciprocating in the cylinder chamber 3 and adapted to deliver a hammer blow upon the end of a tool 4, or, as herein shown, upon the end of an interposed striking pin or tappet 5. The latter has an enlarged head at its forward end and a rear portion projecting into the cylinder chamber and within the path of the hammer piston, such striking pin being an old and well-known expedient in pneumatic hammer drills and riveters to permit the use of a tool having a straight shank.

The tool, or drill-bit, 4 is herein shown as consisting of a straight piece of steel having a hexagonal cross-section and fitting a correspondingly shaped sleeve or bushing 6, which latter is fixedly held in the forward end of the cylinder member by any usual chuck or clamping device.

The rear end of the cylinder is covered

and closed by the valve block consisting of the forward section 7 and the rear section 8, 55 the two being doweled together and to the cylinder by the dowel pin 9, and being seated in a chamber formed in the head block 10 between which and the cylinder they are securely clamped by the usual tie-rods (not 60 herein shown).

Pressure fluid is supplied to the supply chamber 12' formed in the head block, and passes thence to the supply passage 13 and the pressure supply space 11 in the head 65 block through any suitable means such as the flexible hose 12, the hose being attached to the rear of the head block, and its supply of pressure fluid to the supply space being regulated by a common form of push throttle 70 valve 14, the latter being subjected to a constant fluid pressure at its forward end and, at its rear end, to the pressure of the push handle 15, as the said handle is held by the operative and the tool forced or held to the 75 work.

Within the valve block, there is provided a valve chamber in which is located the pressure-actuated, annular or shell-like controlling valve 16, adapted to control the 80 movements of the piston. Any suitable form of valve may be employed, but herein I have shown one of a construction similar to that disclosed in my prior Patent 1,095,848, dated May 5, 1914. Pressure fluid passes to the 85 said valve chamber from the supply space 11, through the passages 17 and is distributed under the control of the valve alternately to opposite ends of the cylinder chamber 3. 90

In order to provide an efficient and always available means for cleaning the cuttings from the drilled hole, I have provided means for supplying a regulatable quantity of live, high-pressure fluid (which is preferably 95 compressed air, but which may be steam or other gaseous pressure fluid) to the drilled hole, where it may be utilized either alone or in conjunction with water also applied thereto to expel the cuttings. Preferably, 100 though not necessarily, as shown in the illustrative embodiment, such supply of pressure fluid is diverted from the pressure fluid supply passage to the drill engine and may be admitted to the drilled hole through 105 the hollow drill-bit by means of an

axially arranged hollow feed-tube projecting through the reciprocatory hammer piston, the supply of such pressure fluid to the tube and the drill-bit being under the control of a controlling valve, which herein is adapted to be regulated independently of the throttle valve of the engine.

To this end, the drill-bit is provided with a central longitudinal passage 18, extending from end to end, which passage alines with a similar passage in the striking pin 5, the latter being proportioned to have a sliding fit on the feed-tube 19, as has also the hammer piston 2. Such feed-tube preferably terminates as shown, within the striking pin 5, in such a manner that its end is protected thereby and the bore of the latter cooperates with the tube in delivering the cleansing agent to the longitudinal passage 18 in the drill bit. As shown, this feed tube 19 also extends axially through the hollow valve 16, and through a rearwardly projecting plug portion 20 on the piston, which plug portion is adapted to enter the controlling valve and partly fill the same on the rearward movement of the piston.

The feeding tube may be supported in any suitable way, but preferably it is held in the rear portion 8 of the valve block upon a slightly yielding seat, so as to reduce the injurious effect of the vibrations of the tool upon the tube. To this end the valve block portion 8 has a pocket or recess in which there is provided a quantity of yieldable packing material 21, such as leather or rubber, and the tube is provided with a shoulder or flanged portion 22, which herein is formed by brazing to the tube a disk-like washer or collar.

40 To secure the tube upon its seat, the walls of the chamber or recess in the rear valve block member are threaded to receive a clamping member 23, the forward end of which abuts against the flange 22, and by 45 means of which the said flange may be pressed firmly down against the yielding base 21. The interior of the member 23 is counter-bored to provide a chamber or supply space 24 about the open end of and communicating with the feed-tube. At its forward end it is transversely slotted at a plurality of points 25 to provide admission to the chamber 24 of pressure fluid from a circumferential groove 26, which latter communicates with supply passages 27 and 28, the latter communicating directly with the pressure supply passage 13, and herein outside of the control of the main throttle 14. The member 23 therefore constitutes also a 50 thimble or cage about the open end of the tube admitting pressure fluid freely thereto from the groove 26. The supply of compressed air, or the pressure fluid entering the passage 27 passes therefore freely to the 55 chamber 24, into the tube 19, and through

the hollow drill-bit 4 to the cutting edge thereof, where it is discharged into the hole. The member 23 has a hexagonal or other suitably shaped end 40 and is provided with the lock-nut 41.

70 In the illustrative embodiment of the invention, I contemplate supplying the drilled hole with water from an independent source and by means (not herein shown) outside of the drill-bit. This, for example, may be 75 done by means of a hose or pipe discharging into the drilled hole.

To regulate the supply of pressure fluid delivered to the feed-tube, I have interposed between the feed-tube and the main pressure supply a separate controlling valve 29, said valve herein being interposed between the supply passages 27 and 28. The valve consists of a stem portion 29 having a threaded part 30 engaging with a correspondingly threaded portion of the casing 31, the latter being threaded into the head block. The valve is provided with a handle 32, by which it may be turned and adjusted to any desired position at the will of 90 the operator, whereby the supply of pressure fluid to the tube can be regulated at will.

To fix the valve handle in its different positions of adjustment, the inner face of the handle hub is notched or serrated as indicated. These notches engage with corresponding notches in the outer face of the plunger 33, which plunger is seated in a chamber 35 in the casing 31, but is yieldably pressed outwardly by a spring 34. The plunger is prevented from turning in the casing by means of lugs 36-36, which slide longitudinally in slots in the casing and permit the longitudinal movement of the 105 plunger, while preventing rotative movement thereof. When the handle is turned, the plunger is wedged back, permitting the teeth on the handle hub to slip over the teeth on the plunger, the stem being thereby screwed in or out to close or open the supply passage. When the handle comes to rest, however, the teeth of the plunger snap into the notches of the handle and lock the handle against accidental movement due 110 to shocks or vibrations.

By the use of the described form of apparatus, particularly where employed with the independent regulating valve of the pressure fluid supply, I am enabled to conduct 120 a supply of pressure fluid under pipe line pressure directly into the drilled hole, and in varying amounts, independent of the operation of the tool. Thus as the hole deepens, and more force is required to remove 125 the cuttings, a greater quantity of pressure fluid may be admitted, without in any way affecting the operation of the tool or impairing its efficiency. I am thus enabled to vary the conditions of the pressure fluid sup- 130

plied to the drilled hole to meet the varying conditions of operation, without in any way affecting the efficient operation of the tool.

5 While I have herein shown and described for purposes of illustration one specific embodiment of the invention, it is to be understood that the same is not limited to the details shown, nor to the relative arrangement 10 of parts or precise application of the invention disclosed, but that extensive deviations may be made therefrom, without departing from the spirit of the invention.

Claims.

15 1. In a rock drill, the combination with a cylinder having a pressure fluid supply space at the rear thereof, of a piston hammer adapted to strike a hammer blow, a feed tube passing axially through the piston

20 and communicating with the pressure fluid supply space at the rear of the cylinder, a throttle between the said tube and the pressure fluid supply space, and a second throttle between the pressure fluid supply space and 25 the cylinder.

2. In a rock drill, the combination with a cylinder having a pressure fluid supply chamber at the rear end thereof, of a hammer piston, a hollow controlling valve at 30 the rear of said cylinder, a supply tube passing through said valve and hammer piston and opening into a pressure supply space at the rear of said valve, and means for supplying live pressure fluid to said supply 35 space.

3. In a rock drill, the combination with a cylinder, a piston therein, a head block having a fluid supply chamber, and a feed tube supported in said head block for supplying 40 pressure fluid to the drilled hole, said head block having a passage leading from said fluid supply chamber to said cylinder and a passage leading from said supply chamber to said feed tube, of separate valves independently controlling the passages in said head block, respectively.

4. In a rock drill, the combination with a cylinder, of a hammer piston, a hollow drill-bit, a controlling valve for controlling the 50 movements of the piston, a valve block, and a feed-tube supported in said valve block and passing through said valve and cylinder into said drill-bit.

5. In a rock drill, the combination with a cylinder, of a hammer piston, a hollow drill-bit, a feed-tube passing through said piston and communicating with said drill-bit, and a yieldable part against which the tube is clamped.

60 6. In a rock drill, the combination with a cylinder, of a piston, a feed-tube passing through the piston, a shoulder on the feed-tube, and a clamping member engaging said shoulder and clamping said tube to a seat.

65 7. In a rock drill, the combination with a

piston, of a cylinder member, a feed-tube passing through the piston, a shoulder on the feed-tube, a seat therefor on the cylinder member, a chambered clamping member surrounding the end of the tube and adapted to clamp said shoulder to a seat, and means to feed fluid to the chambered clamping member.

70 8. In a rock drill, the combination with a cylinder member, of a piston, a feed-tube passing through the piston, a shoulder on the feed tube, a seat in said cylinder member for said shoulder, and a chambered exteriorly threaded member engaging the cylinder member and surrounding said tube and 75 adapted to clamp said shoulder to its seat and provided with lateral fluid admission openings communicating with said chamber.

9. In a rock drill, the combination with a cylinder, of a piston, and a feed-tube passing through the piston and having a clamping shoulder or flange.

10. In a drill, the combination with a cylinder, of a hammer piston, a shell valve at the rear of the piston, a feed tube passing 90 axially through the piston and the hollow interior of the shell valve, a fluid pressure supply chamber, a throttle valve between the same and the said shell valve, passages connecting the rear of said tube with the 95 said pressure supply chamber, and a throttle valve controlling said passages.

11. In a rock drill, the combination with a cylinder and piston and a controlling valve therefor, of a fluid pressure inlet, a normally closed throttle valve interposed between the inlet and the cylinder, means operative to open said throttle valve when the drill is presented to the work, means for feeding fluid pressure from said inlet to the drill 100 hole, and means separate from and independent of said throttle valve for controlling said feeding means.

12. In a rock drill, the combination with a cylinder and piston and a controlling valve 110 therefor, of a fluid pressure inlet, a throttle valve normally held closed by the pressure supply interposed between the inlet and the cylinder, means operative to open said throttle valve when the drill is presented to the 115 work, means for feeding fluid pressure from said inlet to the drill hole, and means separate from and independent of said throttle valve for controlling said feeding means.

13. In a rock drill, the combination with a cylinder and piston and a controlling valve therefor, of a fluid pressure inlet, a drill handle, a normally closed throttle valve operated by the handle and interposed between the inlet and the cylinder, means for feeding fluid pressure from said inlet to the drilled hole, and means separate from and independent of said throttle valve for controlling said feeding means.

14. In a rock drill, the combination with 130

- a cylinder and piston and a controlling valve therefor, of a fluid pressure inlet, a drill handle, a throttle valve normally held closed by the pressure supply and operated 5 by the handle, said valve being interposed between the inlet and the cylinder, means for feeding fluid pressure from said inlet to the drilled hole, and means separate from and independent of said throttle valve for controlling said feeding means. 10
15. In a rock drill, the combination of a casing providing a pressure supply chamber, a cylinder and piston alined with said casing, control and throttle valves within the cross-sectional limits of the casing and cylinder for governing the admission of fluid from said supply chamber to said cylinder for actuating said piston, a supply conduit for feeding live pressure gaseous fluid from 20 said supply chamber to the drilled hole also within the cross-sectional limits of the casing and cylinder, and a control valve separate from and independent of said throttle valve for said conduit located on the casing. 25
16. In a drilling machine, the combination with a cylinder member, of a piston operating therein, a closure plate for the cylinder member having a rearwardly opening socket, a tube extending through the piston member 30 and having a flanged end located in the socket of the closure plate, a plug threaded into the socket and bearing against the flange, and means for introducing fluid into the tube and including lateral ports opening 35 through said plug. 40
17. In a drilling machine, the combination with a cylinder member, of a head block secured to the rear end thereof, a closure interposed between the head block and cylinder member and held in place thereby, said closure having a central socket, a reciprocatory piston operating in the cylinder member, a tappet engaged by the piston, a tube having a flanged end in the socket of the closure 45 and having its other end in the tappet, means for securing the said end in the socket, and means for introducing motive fluid into the tube. 50
18. In a drilling machine, the combination with a cylinder member, of a reciprocatory piston operating therein, a member carried at the rear end of said cylinder and having a socket therein, a tube extending into said piston and having a flanged end 55 extending into the socket in said member, and means for securing the flanged end of said tube in said socket having a lateral port therein communicating with said tube. 60
19. In a drilling machine, the combination with a cylinder member, of a reciprocatory piston operating therein, a member carried at the rear end of said cylinder and having a socket therein, a tube extending into said piston and having a flanged end extending 65 into the socket in said member, and a plug seated in said socket and engageable with the flanged end of said tube having a lateral passage therein communicating with said tube. 70
20. In a drilling machine, a cylinder, a reciprocatory piston operating therein, a member carried at the rear of said cylinder and having a socket therein, a tube extending into said piston and having a flanged end disposed in said socket, packing surrounding said tube and disposed in said socket, and means for clamping said tube and packing in position in said socket. 75
21. In a drilling machine, a cylinder, a piston reciprocable in said cylinder, a block 80 secured to the rear end of said cylinder, a tube projecting into said cylinder and through said piston, means for securing one end of said tube to said block having a lateral port therein communicating with said tube, means forming a fluid passage extending to said port, and a valve in the passage controlling the supply of fluid passing therethrough. 85
22. In a rock drill, the combination with a cylinder having a rear head, of a feed tube 90 extending through said cylinder and supported in said head, said feed tube being removable through said head from the rear thereof, and means at the rear of said head 95 for retaining said tube in position, said means when in operative position relative to the head preventing removal of the tube from the head, but upon removal from said head permitting said tube to be removed 100 rearwardly through said head. 105
23. In drilling apparatus, the combination with a motor comprising a cylinder member and a piston operating therein, of means for delivering motive fluid to the piston to actuate it including a rear passage opening into the cylinder member, a valve controlling such passage and coaxially disposed with respect thereto, a hollow tool to be operated on by the piston, and means extending through the valve for delivering 110 cleansing fluid to the tool. 110
24. In drilling apparatus, the combination with a motor comprising a cylinder member and a piston operating therein, of means for delivering motive fluid to the piston to actuate it including a rear passage opening into the cylinder member, a valve controlling such passage, a hollow tool to be operated on by the piston, and means for 115 delivering cleansing fluid to the tool including a tube extending through the valve and piston and having a relatively fluid tight engagement with the latter. 120
25. In drilling apparatus, the combination with a cylinder member having a head and a bushing arranged at the inner side of the head, of a piston operating in the cylinder member, means for supplying motive fluid to the cylinder member through the 125 130

bushing, and means for supplying cleansing fluid through the head and bushing to a tool operated on by the piston.

26. In drilling apparatus, the combination with a cylinder member having a head and a bushing arranged at the inner side of the head, of a piston operating in the cylinder member, means engaged with the bushing for supplying motive fluid to the cylinder member, and a tube mounted on the head and passing through the bushing and piston to deliver cleansing fluid to a tool operated on by the piston.

27. In drilling apparatus, the combination with a cylinder member, of a piston operating therein, a tube fixedly secured at one of its ends to said cylinder and serving to supply cleansing fluid to a tool operated on by the piston, and means surrounding the tube for controlling the flow of motive fluid supplied to the cylinder member for actuating said piston, said piston having an area substantially equal to the entire cross sectional area of said cylinder subjected to fluid pressure during its percussive stroke.

28. A rock drill comprising a cylinder, a piston reciprocable therein, a rear head for said cylinder, a hollow distributing valve controlling the movement of said piston and arranged in alignment with said cylinder and within said rear head, and a tube mounted in said rear head and extending through said valve and piston for supplying cleansing fluid to a hollow drill steel, said piston being bored to provide a sliding fit with said tube and having an extension formed thereon adapted to telescope with said hollow valve during less than the entire stroke thereof in either direction.

40 29. A rock drill comprising a cylinder, a piston reciprocable in said cylinder, fluid

distribution means for said drill comprising a valve whose axis is parallel to an element of the surface of said cylinder, and a tube for supplying cleansing fluid to a 45 hollow drill steel extending through said valve and piston, said piston having a longitudinal bore forming a sliding fit with said tube and having at least one end thereof of an area equal to the differences in area 50 between the cross sectional areas of said cylinder and of said bore exposed to fluid pressure and coöperating in effecting movement of said piston.

30. A rock drill comprising a cylinder, a rear head therefor, a piston reciprocable in said cylinder, a fluid distribution means for said drill comprising a port opening through the rear head of said cylinder into the rear end thereof and a hollow valve controlling 60 said port, and a fluid supply tube extending through said piston for supplying cleansing fluid to a hollow drill steel actuated by the latter, said piston having a bore extending longitudinally thereof and providing a 65 sliding fit with said tube and having at the rear end thereof an area equal to the differences in area between the cross sectional areas of said cylinder and of said bore adapted to be subjected to motive fluid for 70 effecting the striking of a blow by said piston and said tube being detachably mounted in said rear head and removable axially through said hollow valve.

In testimony whereof, I have signed my 75 name to this specification, in the presence of two subscribing witnesses.

GEORGE H. GILMAN.
